(57) **CLAIM**

I claim the ornamental design for a collapsible beverage container, as shown and described.

DESCRIPTION

FIG. 1 is a top front perspective view of a collapsible beverage container showing my new design in open in use position;

FIG. 2 is a front view thereof;

FIG. 3 is a right side view thereof, the left side view being a mirror image thereof;

FIG. 4 is a rear view thereof;

FIG. 5 is a top plan view thereof;

FIG. 6 is a bottom plan view thereof in both open and collapsed position;

FIG. 7 is a top front perspective view of the collapsible beverage container in collapsed position;

FIG. 8 is a front view thereof;

FIG. 9 is a right side view thereof, the left side view being a mirror image thereof;

FIG. 10 is a rear view thereof; and,

FIG. 11 is a top plan view thereof.

The broken lines in the drawing depict environmental subject matter only and form no part of the claimed design.
